UNITED STATES PATENT OFFICE.

MORLAND MICHOLL DESSAU, OF LONDON, ENGLAND.

TOY TRUMPET.

Application filed November 8, 1924. Serial No. 743,703.

To all whom it may concern:

Be it known that I, MORLAND MICHOLL DESSAU, a citizen of the United States, residing at 14, Mincing Lane, London, England, have invented a new and useful Toy Trumpet, of which the following is a specification.

My invention relates to an improved construction of toy trumpet and has for its object to provide a simple method of constructing a toy trumpet of resilient material so that it will not be damaged by rough usage and will not cut or injure the child or any other person.

According to this invention, I construct a toy trumpet of raw plantation rubber crêpe or the like formed to the desired shape and provided with a reed or sound producing instrument in the smaller or mouthpiece end.

The trumpet may be conveniently constructed from sheet material cut to the desired shape to form the blank which is afterwards rolled and connected at its edges to form the trumpet. The blank may conveniently consist of a narrow tapered strip which when rolled into a circle will form a hollow conical tubular piece, and at the end of the blank may be formed a larger portion which when rolled round with the other piece will form

a splayed out end of trumpet shape. If desired the splayed out end may be formed separately and attached to the conical tubular portion by solution or other suitable means. The end of this portion may be turned over and secured to itself so as to form a reinforced or stiffened edge, and a suitably shaped mouth-piece may be attached to the small end of the conical tubular portion. In this end may be arranged a suitable reed or other sound producing device so that blowing through the mouthpiece will cause the trumpet to be sounded.

The tubular portion of the trumpet may be reinforced by a strip or strips of resilient material such as whalebone or the like. The reinforcing strip or strips may be secured within the tubular portion by engaging the ends in loops secured within the tubular portion of the horn or one or more resilient strips may be embodied in the longitudinal seam or seams of this portion. These strips tend to maintain the horn straight under ordinary circumstances but allow it to be readily bent and yet return to its original shape.

If desired the trumpet may be made of a plain conical tubular form, the smaller end of which forms the mouth-piece and is provided with a reed or other sound producing device, whilst the other end is turned over to form a reinforced edge and comprises the open end of the horn. Such a horn may be made of a size to fit upon a finger or hand, and in this case since the open end of the horn is obstructed, the air will escape through the pores of the plantation rubber crêpe so that the horn will be sounded in spite of the obstruction. A suitable loop or handle may be attached to the horn at its side and preferably comprises a strip of whalebone or other resilient material covered with raw plantation rubber crêpe and secured at its two ends to the tubular portion of the horn.

The trumpets may be made up of a series of rings connected together by latex, solution or the like and serrated or plain rings may be secured over the joins. A strip of rubber crêpe or the like may be rolled up in spiral form to make the trumpet and secured together along the spiral join. A covering strip may be secured over the spiral join if desired.

A horn or trumpet constructed according to my invention, will stand an unlimited amount of rough usage, and knocking about, and yet retain its proper shape and operate correctly. It may be immersed in water without any detrimental effect and may in fact be used by a child whilst being bathed. Its soft and resilient nature gives it the further advantage that no cuts or other injury can be caused to children playing with it and it may be safely left to quite small children without any danger.

In order that my invention may be readily understood, reference is made to the accompanying drawings, in which:—

Fig. 1 is a longitudinal section through a trumpet constructed according to my invention.

Fig. 2 shows a slightly modified form of trumpet in elevation, and

Fig. 3 shows a further small trumpet of a simplified form.

Referring to Fig. 1, the body 1 of the trumpet is formed from a strip of raw plantation rubber crêpe rolled up into a tapering tubular form as shown, the edges being caused to adhere either with or without the

- 2
- addition of suitable latex, solution or the like. Into the small end 2 of this tapering tubular body 1 of the horn is inserted a suitable reed or other sound producing device 3. 5 This is arranged of such a size that it causes the end of the tapering tubular body piece 1 to be swelled out slightly at 4 so that the end 2 will form the mouthpiece. At the other end of the body 1 of the trumpet is 10 provided a flared outlet 5. This may be formed in one with the blank for forming the tubular body 1 so that when rolled up the end 5 will assume the flared shape shown. This flared end 5 may however be formed 15 from a separate piece of raw plantation rubber crêpe rolled up to the desired shape and its edges connected either with or without the application of suitable latex or solution. The flared end 5 is then attached to the end 20 of the body 1 at 6, so that it will adhere thereto either with or without the addition of latex or solution. The enlarged end of the flare 1 is provided with a turned-in edge 7 which strengthens and stiffens the same. 25 In order to give a reasonable amount of stiffness to the trumpet, a stiffening member 8 may be arranged in the body portion 1. This stiffening member is shown of a bowed shape so that it engages near the centre of 30 its length with one side of the tubular body 1, whilst its two ends are held in loops 9 of plantation rubber crêpe or the like connected to the other side of the tubular body near to the opposite ends thereof. The stiffening 35 member 8 preferably comprises a strip of whalebone or other flexible material encased in an outer covering of raw plantation rubber crêpe or the like.
- Referring now to Fig. 2, this shows a 40 similar type of trumpet but of slightly different construction. The conical tubular body 10 is formed in the same manner as described with reference to Fig. 1, but in this case the material is printed or otherwise coloured or provided with a decorative pattern upon its surface. The flared end 11 is formed separately and attached to the body 10 by means of a band 12 of raw plantation rubber crêpe or the like cemented or otherwise 45 secured around the junction. The mouth-piece 14 is shown of plain material and a suitable reed or sound producing device is provided therein so that blowing through the mouthpiece will cause the 50 trumpet to be sounded. A suitable internal stiffening device similar to that shown at 8 in Fig. 1 may be incorporated in the body 10 if desired, but in short trumpets this may be omitted. A handle 15 is shown attached by 55 its two ends to the exterior of the body 10. This handle comprises a bowed strip 16 of whalebone or other flexible material encased in an outer covering of plantation rubber crêpe or the like by which its two ends are 60 secured to the exterior of the body 10 by 65

causing them to adhere thereto either with or without the assistance of latex, solution or the like.

Fig. 3 shows a smaller form of trumpet comprising a simple conical body 20 seamed together at 21 and provided with an in-turned end 22 to stiffen the latter. A reed or other sound producing device 23 is provided in the smaller end or mouthpiece 24 of the trumpet. The exterior of the trumpet 70 may be suitably decorated as for instance by suitable bands of colour as shown in the drawing. This form of trumpet may be conveniently made of comparatively porous plantation rubber crêpe or the like or the 75 material may be provided with fine perforations, so that even if a child's hand or finger be inserted in the larger end 22 of the trumpet it may still be sounded by blowing through the mouth-piece, the body of the 80 trumpet being sufficiently porous to enable the air to escape through the material.

The trumpets are submitted to any suitable cold or other vulcanizing process, but it is preferred to use the process known as 90 the Peachey cold vulcanizing process.

Trumpets constructed according to this invention are almost indestructible and may be safely left in the hands of even small children as they cannot do damage to themselves or to others since the trumpets are of 95 a soft and flexible nature.

I claim:—

1. A toy trumpet comprising a hollow body formed of rubber, a bow-shaped stiffening member secured at its ends to the hollow body, a mouthpiece formed at one end of the hollow body and a sound producing device within said mouthpiece.

2. A toy trumpet comprising a hollow 105 tapering body formed of plantation rubber crêpe, a bow-shaped member formed with a core of stiff yet flexible material and with an outer covering of rubber, said bow-shaped member being secured at its two ends 110 to said hollow body, a mouthpiece formed at the smaller end of the hollow body and a sound producing device within said mouthpiece.

3. A toy trumpet comprising a hollow 115 tapering body formed of rubber, a flared outlet piece formed of rubber and secured to the larger end of the hollow body, a doubled over edge to said flared outlet piece, a bow shaped member formed with a core 120 of stiff yet flexible material and with an outer covering of rubber, said bow shaped member being secured at its two ends to the hollow body, a mouthpiece formed at the smaller end of the hollow body, and a sound producing device within said mouthpiece.

4. A toy trumpet comprising a hollow 125 tapering body formed from plantation rubber crêpe, a flared outlet piece formed from plantation rubber crêpe and secured to the 130

larger end of the hollow body, a doubled over edge to said flared outlet piece, a bow shaped member formed with a core of stiff yet flexible material and with an outer covering of plantation rubber crêpe, said bow shaped member being located entirely within the hollow body with its two ends engaging loops secured on one side of the hollow body, the middle part of said bow shaped member

contacting with the opposite side of the hollow body, and a sound producing device located in the smaller end of the hollow body, said sound producing device stretching the said end of the hollow body slightly and causing it to assume the shape of a ¹⁵ mouthpiece.

MORLAND MICHOLL DESSAU.
